UNITED STATES PATENT OFFICE.

JOHN PONSTEIN, OF CHICAGO, ILLINOIS.

BOLSTER FOR CARS.

SPECIFICATION forming part of Letters Patent No. 596,122, dated December 28, 1897.

Application filed July 9, 1897. Serial No. 643,932. (No model.)

To all whom it may concern:

Be it known that I, JOHN PONSTEIN, a citizen of the United States, residing at Chicago, in the county of Cook and State of Illinois, have 5 invented a new and useful Improvement in Bolsters for Cars, of which the following is a specification.

My invention relates to improvements in built-up metallic car-bolsters; and the principal object of my invention is to provide a metal bolster that will be of simple construction and at the same time furnish the greatest strength and rigidity for the weight of metal employed. I attain this object by the mechanism illustrated in the accompanying drawings, in which—

Figure 1 is a side view of the entire device. Fig. 2 is a top view thereof. Fig. 3 is a side view of the end of the bolster, showing in 20 detail the method of construction thereof. Fig. 4 is a top view of the end portion of the bolster. Fig. 5 is a detail, viewed from the under side, of the method of joining the ends of the upper and lower members of the trusses, 25 to be hereinafter described. Fig. 6 is a side view in detail, and Fig. 7 a top view in detail, of the central portion of the bolster. Fig. 8 is a sectional view, taken through the center of the turn-table, on the line 8 8, Fig. 6. Fig. 30 9 is a side view of the principal end piece which carries the guide-bars and spring-seats. Fig. 10 is a top view of said end piece. Fig. 11 is a side view of the intermediate brace.

Similar letters refer to similar parts throughout the several views.

This bolster differs from those previously constructed in that it consists of two separate trusses joined together in the manner to be described.

40 The top pieces of the truss or compression members A A are angle-bars so placed relatively to each other that when the bolster is in its normal position the two inner flanges a a are parallel and vertical and the two horizontal flanges a' a' extend outward in opposite directions.

The angle-bars A A are preferably bent or bowed to slope slightly downward from the middle toward the ends, where they are fastened to the lower or tension members B B. Said members B B are flat bars bent as shown 45 and having their flat surfaces parallel to and

in contact on the outside with the inner flanges a a of the angle-bars A. The bars B B are long enough to make a return-bend 55 at their ends upon the vertical flanges a a of the angle-bars A. Said bars B B are for the purpose of making this return-bend slightly bowed from their ends inwardly, as shown in dotted lines in Fig. 7. There are thus formed, 60 when the center piece, to be described, is included, two separate trusses having a common center post.

The two trusses are joined together at the ends by means of a piece C and a plate D. 65

The piece C is preferably a malleable casting, and consists of a flat plate C', designed to cover the bottom of the bolster at the end thereof, and having approximately at right angles to said plate the lugs or ribs c c, webs 70 c' c', end cover c², and guide-bars c³ and spring-seats c⁴. The lugs or ribs c c serve to hold the ends of the trusses in place and furnish means for riveting said ends of said trusses onto said piece C, while the webs c' c' further increase 75 the strength of said piece and the end cover c² serves to give a neat appearance to the end of the bolster.

On the sides of piece C are the guide-bars c³ c³, which permit the vertical motion of the 80 bolster upon the car-springs c⁵ c⁵, and the spring-seats c⁴ c⁴ are placed on the under side of the plate C for the purpose of holding the upper ends of said springs in position.

The plate D extends across and is riveted 85 to the horizontal flanges a' a' of the angle-bars A, adding strength and a finished appearance to the end of the bolster.

The two trusses are joined together in the middle by means of two pieces E and F, which 90 are preferably of malleable cast-iron. The upper piece E is the center bearing or turn-table and has an aperture e in the center to receive the king-bolt, (not shown,) and also has flanges e' e', which overlap the angle-bars 95 A A and a portion of the piece F and hold them firmly in position. Piece F is the center post or strut of the two trusses and is box-shaped and has grooved rests f f to receive the vertical flanges a a of the angle-bars A, 100 and has also shallower rests f' f' near its lower extremity to receive the flat tension-bars B B. Webs or ribs f² are provided to give necessary stiffness and strength, and the

sleeve or boss f^3 registers with the aperture e in piece E to receive the king-bolt. Lips or lugs f^4 furnish stock for riveting piece F to the bars B B.

5 The bolster is further reinforced by strong braces G G, placed about midway between the center and ends of the bolster to prevent the bolster from buckling under severe strain and also to prevent any whipping or jarring, 10 which might tend to loosen the riveting.

The guides or stop-blocks H H, placed upon the top of the bolster, serve as rests for the body of the car, limiting the inclination of the car in rounding curves.

15 The principle of the truss has been heretofore employed in the construction of car-bolsters; but no bolsters have been built of two separate trusses, using angle-bars as the compression members. The advantage of this 20 over previous constructions is evident when it is considered that the greatest strain on the compression member lies in the plane of the truss. For example, when the trussed bolster is subjected to great strain the tendency is for the compression member to bend either up or down.

In a channel-bar the greatest resistance to transverse strain lies in the direction of the width of the main body or central portion of 25 the bar, and when such bars have been used in trussed bolsters they have been so placed that the body of the channel-bar was at right angles to the direction of the greatest strain, thus depending for strength mostly on the 30 flanges. In such constructions much of the material is almost useless, as it furnishes very little strength in proportion to its weight; but in my improved construction by the use of angle-bars the waste stock formerly employed is dispensed with, with the result that 35 my improved bolster, while retaining practically the same strength as the prior construction, is much lighter in weight. Conversely, if a lighter bolster is not desirable 40 my improved construction furnishes much greater strength without necessitating a greater weight of metal than was employed in the previous construction. The width of 45 the bolster may also be varied without materially affecting its weight.

50 Another important feature of this bolster is the method of joining the tension member or bar B and compression member A, as shown in Figs. 3, 4, and 5. The tension-bar B makes 55 a return-bend on the vertical flange a of the angle-bar A and is held in place by rivets through the angle-bar, return-bend, and the lugs or ribs c on piece C. As has already 60 been said, the tendency under strain is for the compression member to bend vertically—that is, up or down—and if the tension member is so joined to said compression member 65 as to lie horizontal thereupon, as in some previous constructions, the rivets would then be subjected to tension; but the tension member

B being in a vertical position, as shown, the rivets are under shearing stress only, which is well known to be their condition of greatest strength.

It is evident that the details of construction 70 of my device may be considerably varied without altering the principles of my invention; and I therefore do not limit myself to the details above described.

What I claim as new, and desire to secure 75 by Letters Patent, is—

1. A car-bolster composed of two separate trusses properly joined together, each truss having separate tension and compression members.

2. A double-trussed car-bolster employing angle-bars, as the compression members thereof.

3. A car-bolster composed of two suitably joined, similar and parallel trusses, having a 85 common center post or strut member, and employing angle-bars as to the compression members thereof.

4. A car-bolster formed of two separate trusses properly connected together, each 90 truss having for its upper member an angle-bar; the lower member of said truss being a flat bar, so arranged that the flat side thereof stands vertically; the upper and lower members of said truss being braced and connected 95 by suitable means, substantially as set forth.

5. A car-bolster consisting of two separate trusses, employing angle-bars for the compression members thereof, and flat bars for the tension members thereof, said flat bars 100 making a return-bend upon the vertical flanges of said angle-bars.

6. A car-bolster composed of two separate trusses, each truss having for its upper member an angle-bar, and for its lower member a 105 flat bar, with the flat side thereof, arranged vertically; the ends of said lower flat bar making a return-bend around the extremity of the vertical flange of the angle-bar; in combination with an end piece having parallel ribs 110 held in place by transverse webs, forming grooves, for the reception of the ends of the trusses; and central braces or struts, connecting said trusses with each other, and also connecting the upper and lower members of said 115 trusses, substantially as described.

7. In combination with a double truss for a car-bolster, having angle-bars and flat bars, an end piece, composed of an underlying flat plate, having two grooves, or channels composed of parallel ribs, properly braced for the 120 reception of the ends of said trusses, whereby the members of said trusses may be riveted and held in position in such manner, that a shearing strain only will be brought upon the 125 rivets, substantially as described.
